UNITED STATES PATENT OFFICE.

JOHN B. ARCHER, OF OAKLAND, CALIFORNIA.

FURNACE.

SPECIFICATION forming part of Letters Patent No. 638,689, dated December 12, 1899.

Application filed July 24, 1899. Serial No. 724,999. (No model.)

To all whom it may concern:

Be it known that I, JOHN B. ARCHER, a citizen of the United States, residing at Oakland, in the county of Alameda and State of California, have invented certain new and useful Improvements in Furnaces; and I do hereby declare the following to be a full, clear, and exact description of said invention, such as will enable others skilled in the art to which it most nearly appertains to make, use, and practice the same.

This invention relates to improvements in furnaces.

In the drawings, Figure 1 is a vertical longitudinal section of a boiler provided with a furnace constructed in accordance with this invention. Fig. 2 is a plan view of a furnace as shown in Fig. 1, the boiler and supporting-walls being removed. Fig. 3 is a detail view 20 in plan of a supplemental draft apparatus constructed in accordance with this invention and shown in its twin or double construction. Fig. 4 is a cross-section of the same, taken on the lines X' X'.

25 The object of the present invention is to consume the heavy gases which come off from the combustion in the form of smoke and to increase the efficiency in the combustion itself.

With these objects in view the invention 30 consists in the production and use of an apparatus for spreading the heavy gases in an attenuated sheet and to rotate the same horizontally in the combustion-space to cause a cyclonic movement of the same, and whereby 35 it is returned for part of the rotation against the natural line of draft in the furnace and into the combustion.

The appliance, as shown in Figs. 3 and 4, is introduced in the side walls of the fire-box of 40 a furnace in such a manner that the fire-box is surrounded on all sides. The appliance consists of a hollow box A, preferably rectangular in cross-section, from the interior of which protrude twyters A'. It is designed that 45 the hollow box should be contained within the walls of the fire-box and the face of the same be protected by fire-brick B or suitably-constructed tile or other refractory material. The twyters are centrally bored, as shown in 50 Fig. 3 of the drawings, in such a manner that the perforations are at an angle to the box A horizontally. The inclination of these twyters

is in the same general direction when followed from the entrance end of the box A—that is to say, the various sections or side extensions of the box A are provided with twyters set at the same angle when viewed in succession, producing in the completed box A a set of twyters on the one extension or side diametrically oppositely inclined to the adjoining extensions and directly oppositely inclined to the twyters of the opposite extension. When the air is forced into the box A and from the box through the twyters, the immediate effect is to produce a rotary action of 65 the air as it is ejected into the central or combustion space over the fire-space of the fire-box at the desired distance above the fire.

The box A is provided with an inlet extension A², extended beyond the front wall of 70 the furnace to receive the connections C' of the main forced-air-draft system C.

The box A is preferably constructed of cast metal. It is placed in the wall of the furnace to surround the fire-box, as shown in Figs. 1 75 and 2. The metal is protected by the facing of fire tile or bricks B.

The preferred location of the box, as shown in Fig. 1 of the drawings, is above the grate-bars sufficiently high to raise the opening of 80 the double or more sets of twyters a suitable distance above the bed of the fire. By this arrangement the jets of air entering through the twyters strike the gases as they come off the fire-bed and mix them with the oxygen of 85 the air, while breaking up any gas volumes which may have formed. The volumes of admixed air and gas are by reason of the arrangement of the twyters given a horizontal and rotary motion of a rapidity proportionate 90 to the force with which the air is driven from the twyters. This rotary motion produces an effect of any centrifugal action to throw the heavier particles outward, which in this case are the uncombusted gases. These strike on 95 the projections formed on the side walls and are broken up and scattered and intermixed thereby.

To provide a surface which will separate and break up the combined air and gas volumes when thrown against the side of the combustion-space by the action above mentioned, I have provided the interrupted projective surface shown in Fig. 1 of the draw-

ings. This surface is produced by the peculiar construction and arrangement of the brick or tile E, which constitute the walls of the combustion-space above the grate-bars. In 5 the drawings the light and dark spaces are used to indicate the ends of the adjacent bricks or tile advanced and receded, respectively. It will be noticed that these tile are triangular in shape and arranged to present 10 one angle of the triangle upward; but I do not confine myself to the particular shape or form of tile or brick. Another effect produced by this construction other than the segregation and disintegration of the gas 15 volume is to present small ends or projections which will become heated to a high degree in a very short time by the combustion in the fire-box. This heating of the tile has an added effect in that when the gas is thrown 20 against them the same is at once raised to combustion-point, and there otherwise escaping gases are utilized. A further advantage gained by this interrupted surface of the fire- 25 box when used in conjunction with the appliance for rotating the gases and flame, as herein described, is that the outer periphery of the gases and the flame is retarded, producing a system of secondary rotations, caused by the air on the inner side of the circle 30 traveling at a greater rate of speed than the air on the periphery, all of which coöperate in producing the purposes for which this invention was designed—namely, the aggregation of the gas volume and the perfect ad- 35 mixture of the oxygen of the air with the same and also the more perfect utilization of the heat thus generated by this complete admixture and intermingling of oxygen of the air and liberated gases from the burning fuel— 40 and also by the perfect combustion thus secured the formation of smoke is absolutely prevented.

The air is injected into the chamber A by means of a forced-draft system consisting of 45 the connections C', which are provided with a valve C², coil C, and the connecting-pipe to the blower C³.

In some instances it is desired to control the force or volume of air in the sides of the

box A independently. This is accomplished 50 by the dampers or gates D, which are provided with handles leading to the outside of the furnace, as shown in the drawings.

Having thus described this invention, it is 55 claimed—

1. The combination with a furnace having a fire-box, of a hollow box or tube arranged to surround said fire-box, obliquely-arranged twyers projecting horizontally from said box or tube and provided with central bores communicating with the latter, and an air-pipe communicating with said box or tube; substantially as set forth. 60

2. The combination with a furnace having a fire-box, of a hollow box or tube arranged to surround said fire-box, obliquely-arranged twyers projecting horizontally from said box or tube and provided with central bores communicating with the latter, a non-combustible facing interposed between said twyers, 65 and an air-inlet pipe communicating with said box or tube; substantially as set forth. 70

3. The combination with a furnace having a fire-box, of a hollow metallic box or tube arranged to surround said fire-box and having an air-inlet branch, obliquely-arranged horizontal twyers projecting from said box or tube and provided with central bores communicating with the latter, and an air-feeding pipe connected to said air-inlet branch, substantially as set forth. 75 80

4. The combination with a furnace having a fire-box, of a hollow box or tube arranged to surround said fire-box, obliquely-arranged twyers projecting horizontally from said box or tube and provided with central bores communicating with the latter, an air-pipe communicating with said box or tube, and an interrupted projective surface located in said fire-box above said box or tube; substantially 85 90 as set forth.

In testimony whereof I have hereunto set my hand this 8th day of May, 1899.

JOHN B. ARCHER.
